UNITED STATES PATENT OFFICE.

EDWARD M. GAREY, OF NEW YORK, N. Y.

DESIGN FOR A COMBINED LAMP AND SUPPORTING BRACKET.

Application filed May 6, 1927. Serial No. 21,874. Term of patent 14 years.

To all whom it may concern:

Be it known that I, EDWARD M. GAREY, a citizen of the United States, and residing at Brooklyn, in the county of Kings, of the city of New York, in the State of New York, have invented a new, original, and ornamental Design for Combined Lamp and Supporting Bracket, of which the following is a specification, reference being had to the accompanying drawings, forming a part thereof.

The figure is a perspective view of a combined lamp and supporting bracket showing my new design.

I claim:

The ornamental design for a combined lamp and supporting bracket substantially as shown.

This specification signed this 5th day of May, 1927.

EDWARD M. GAREY.
